Jas. Wayland, per
Thos. S. Crane, Atty.

UNITED STATES PATENT OFFICE.

JAMES WAYLAND, OF NEWARK, NEW JERSEY.

TRUNK-CATCH.

SPECIFICATION forming part of Letters Patent No. 292,967, dated February 5, 1884.

Application filed June 21, 1883. (No model.)

To all whom it may concern:

Be it known that I, JAMES WAYLAND, a citizen of the United States, residing in the city of Newark, in the county of Essex and State of New Jersey, have invented certain new and useful Improvements in Trunk-Catches, fully described and represented in the following specification and the accompanying drawings, forming a part of the same.

10 My invention consists in the combination, with a spring tongue or hasp, of an unlocking-lever constructed to automatically retain its operative position (when placed therein) until the trunk or box is opened, and then to automatically assume an inoperative position, so that the spring-hasp may not be prevented from engaging its opposed hook when the trunk or box is again closed.

15 It also consists in a special construction of the hooked part of the casing with malleable lugs over the bearings for the lever, so that the same can be inserted and secured in its place without loose pieces for caps.

20 I am aware that an unlocking-lever has been used heretofore, as in United States Patent No. 244,645, issued July 19, 1881, and in other constructions; but the lever was not constructed to automatically assume its inoperative position when the trunk or box was opened, but required to be moved by the operator before the catch could engage and lock as desired.

25 I am also aware that a spring-hasp has been combined with a sliding thumb-piece adapted to automatically assume its inoperative position, like the lever I employ; but in such construction the friction of the parts rendered the movement of the thumb-piece much more difficult and uncertain than that of an unbalanced lever such as I employ, as is obvious from 30 the fact that such constructions are commonly made of unpolished iron castings and generally japanned, so that the parts do not slide easily upon one another. Upon the contrary, the excess of japan at some point, or the imperfect baking of the same, not only prevents the voluntary movement of such small pieces by their own weight, but renders the movement by the operator's finger far from easy. 35 My construction is intended to obviate these 40 defects in former constructions by substituting a lever having a function entirely different

from that used in the Patent No. 244,645, referred to above, in place of the sliding thumb-piece used in another combination, and thus obtaining results not secured by either previous construction. I will describe my construction in detail, and thus indicate the difference of function referred to above.

45 Figure 1 of the drawings represents the lower casing, A, having the fixed hook a 50 therein, and adapted to unlock with a lever-key, F, which is shown in Fig. 2. Fig. 3 shows the form of unlocking device exhibited in the other views beside Figs. 1 and 2, Fig. 4 containing merely the bearings for the lever, 55 the view showing the casing A in perspective, formed of malleable iron, and provided with lugs e, to cover the pivots of the lever D, shown in Fig. 3 at d. Fig. 5 is a front elevation of the catch complete, as it appears when locked, 60 in its operative condition. Fig. 6 is a section of the same, taken on line x x in Fig. 5; but the lever D is shown in the position it occupies when holding the catch unlocked while the trunk remains shut, and the spring-tongue 65 C remains in the casing A. Fig. 7 is an inside view of the upper casing, B, showing the cavity b, in which the spring-tongue operates, the tongue consisting in a flexible plate of metal secured at one end by a rivet, e, to the 70 foot of the casing, and projecting from the opposite end of the casing far enough to penetrate the lower casing, A, and catch upon the hook a, for which purpose it is provided with a slot, s, to act as a hasp.

75 The spring is so bent as to remain normally upon the hook when the trunk is closed, and the upper side of the hook is beveled to make the tongue spring into its place as the casings are forced together in closing the trunk. 80 The casings can only be separated by first pushing or springing the tongue off of the fixed hook a, which may be effected by operating the unlocking device seen in Fig. 8, which is an inside view of the casing A, as constructed 85 with a permanent or attached lever, D. This lever projects through a slot, t, formed in the case below the hook a, and is formed with pivots d, fitted to bearings in the sides of the casing A. It is provided with two bits, r, 90 constructed to project toward and press upon the spring-tongue when the lever is raised, as 95

shown in Fig. 6, but adapted to lie between the tongue and the casing when the lever is pushed downward, as indicated by the dotted lines seen in Fig. 6. The lever thus operates 5 to detach the tongue from the hook when raised, and is held in a raised position against the action of gravity upon the lever so long as the trunk remains closed and the spring presses toward the bits *r*. The levers may 10 thus be left in a raised position while the trunk is unlocked or unfastened at other points, and the catch offers no resistance to the opening of the trunk. As soon, however, as the trunk is opened, the tongues are withdrawn 15 from their contact with the bits *r*, and the levers, being no longer sustained, fall down into their normal position, where they are quite inoperative. The friction of the spring-tongue upon the bit or bits when the tongue is withdrawn 20 from the casing *A* also serves to restore the lever *D* to its normal position, in which it has no effect upon the spring-tongue when the latter is again pressed into the casing in closing the trunk. The catches will 25 therefore operate automatically to lock the trunk when again closed, without any attention being given to the levers after unlocking.

If preferred, the lever may be made detachable, as shown in Fig. 2, and the pivots 30 and bits made to enter a hole, *f*, in the side of the casing, as shown in Fig. 1. With this construction the catch operates to lock the trunk until released by inserting the bits and elevating the lever, as in Fig. 6.

The construction for the bearings in Fig. 4 35 consists in forming open sockets *n* for pivots *d*, and casting malleable lugs *e* above them, which can be bent down to close the bearing when the pivot is inserted in the bearing. In the figure one lug is shown bent down, and 40 the other in the position as when first cast.

From the above description it will be seen that although the lever *D* operates, as in other constructions, in detaching the spring hasp or

tongue *C* from the retaining-hook *a*, it differs 45 in function from other similar levers in automatically assuming its inoperative position whenever the trunk or box is opened. My unlocking-lever also differs from the thumb-piece heretofore used for the same purpose, 50 first, in affording a purchase or leverage for the operator when unlocking the spring-tongue; second, in having an unbalanced portion extending at one side of its fulcrum to operate in turning the bits *r* automatically; 55 and, third, in its adaptation to be made removable to operate as a detached key, as shown in Fig. 2. I therefore disclaim the constructions referred to herein as containing either the sliding thumb-piece or the lever for 60 merely detaching the spring-tongue or hasp; and

I claim the specific combination I have devised in the following manner:

1. The combination, with the casing *B* and 65 slotted spring-tongue *C*, of the casing *A*, formed with hook *a*, slot *t*, and sockets *n*, and provided with the lever *D*, having pivots *d* and bit or bits *r*, the lever being constructed to detach the spring from the hook when elevated, and 70 being held in its elevated position by the pressure of the spring only until the tongue *C* is withdrawn, substantially as herein shown and described.

2. The construction for the bearings of the 75 lever *D* in the casing *A*, consisting in the combination, with the sockets *n*, of the malleable lugs *e*, cast at one side of the socket and bent over the same to inclose the pivots of the lever, as herein shown and described. 80

In testimony whereof I have hereunto set my hand in the presence of two subscribing witnesses.

JAMES WAYLAND.
